UNITED STATES PATENT OFFICE

ERNEST W. DANIELS, OF PHOENIX, ARIZONA

PROPELLER

Application filed December 26, 1930. Serial No. 416,380.

This invention relates to new and useful improvements in propellers.

One object of the invention is to provide an improved propeller device employing a plurality of individual propelling units segregated so that each unit individually supplies itself with fluid and expels said fluid in an individual strata, thus amplifying the propelling power of the device.

10 A further object of the invention is to provide a propeller of the type set forth, which may be utilized in any position found practical, such as for lifting, or moving in a horizontal plane, or for pulling downwardly, and 15 usable in any fluid, such as air, water, gas, or the like.

Another object of the invention is to provide a propeller device including a plurality of superposed planes or wings and forming propeller stages having propellers there-in together with conduits for supplying each stage with the fluid in which the device is used, whereby the supplied fluid is propelled radially of the stages and discharged there- 25 from against the surrounding fluid stratas, thus making for more efficient propulsion.

20 A still further object of the invention is to provide a propeller device including a plurality of superposed planes or wings of low construction and each being air tight excepting for a suitable opening, whereby individual propellers coacting with the opening in each plane tend to draw out the air through said opening and thus tend to enhance the buoyancy of the device.

25 A construction designed to carry out the invention will be hereinafter described together with other features of the invention.

The invention will be more readily understood from a reading of the following specification and by reference to the accompanying drawings in which an example of the invention is shown, and wherein:

30 Figure 1 is a plan view of a propeller constructed in accordance with the invention,

35 Figure 2 is an elevation of the same,

Figure 3 is an enlarged view partly in elevation and partly in vertical section,

40 Figure 4 is a horizontal cross-sectional view taken on the line 4-4 of Figure 3, and

Figure 5 is a detail of the fluid conduits.

In the drawings the numeral 10 designates a support or frame which comprises an upper spider 11, a lower spider 12, posts 13, and standards 14. A bearing cap 15 is carried 55 at the top center of the upper spider and the spider 12 extends from a lower bar 16.

A plurality of concavo-convex planes or wings A, B, C and D are mounted in the frame and between the spiders. The posts 60 13 and the standards 14 penetrate these planes, except that the posts 13 do not extend through the lower plane D, but said plane is secured at its outer edge to said posts by eyebolts 17. The planes A, B, and C, 65 respectively, are carried by spreader wings 18 and 19 which are fastened on the posts 13 and the standards 14 respectively. The upper plane A is of single thickness, while the remaining planes are hollow and of double 70 thickness. These planes may be made of any suitable material, such as sheet metal or an equivalent.

An axial driving shaft 20 extends through the bearing member 16 and terminates in the bearing member 15, which forms a thrust bearing. Propelling stages are formed between the planes and these planes are preferably concentric and are spaced apart sufficiently to receive propellers 21 therebetween, which rotate in said stages. In order to provide snug operating spaces for the propellers, the central portion of each plane B, C, and D is flattened so as to provide upper and lower disk portions 22. The propellers 80 85 are fastened to the shaft 20 by bolts 23.

Concentric cylindrical conduits A-1, A-2, and A-3 are disposed concentrically around the shaft 20 within the spider 11 and between the posts 14. The outer conduit 90 A-1 has its outer end within the standards 14 and its inner end terminates at the under side of the top plane A, as is shown in Figure 3. The ends of the conduits are stepped and the inner end of the conduit A-2 terminates at 95 the under side of the plane B, while the inner end of the conduit A-3 terminates at the under side of the plane C. The propellers extend through the conduits A-2 and A-3.

100 Spiral baffles 25 are arranged in each con-

duit and as each conduit supplies fluids to an individual propeller 21, which fluids are drawn in by said propellers, it is obvious that the baffles will impart a whirling motion to these fluids. The propellers are given a sinuous shape in plan, as is shown in Figure 4, and rotate in a clockwise direction so that the fluids are thrown outward in the stages between the planes. These fluids striking the curved surfaces of the planes are discharged from said planes in streams, thus giving adequate propulsion.

Where the propeller device is used on airplanes or other devices in which the fluid is air, the device may be arranged vertically for lifting, or it may be arranged horizontally for pulling. The impact and displacement resulting from the discharge of the streams from the plane stages, together with the shape 20 of the planes will give a superior propulsion. The same is true where the device is used in water, in which instance it could be used on the bottom or the top, or the side or the end of a vessel, as is obvious.

25 In order to add to the buoyancy of the device the planes B, C and D have openings 26 in their upper sides located so that the ends of the propellers pass over said openings, as is indicated in Figure 3. The planes 30 being otherwise fluid tight the rapidly rotating propellers will tend to draw the fluids out of the hollow planes and thus tend to create a vacuum therein, which will thereby increase the buoyancy of the device.

35 Various changes in the size and shape of the different parts, as well as modifications and alterations, may be made within the scope of the appended claims.

What I claim, is:

40 1. In a propeller device, a plurality of superposed planes, a plurality of propellers rotatable between the planes, and individual means for supplying fluid separately to each propeller.

45 2. The combination set forth in claim 1, with means for imparting a whirling motion to the fluid supplied to said propellers.

50 3. The combination set forth in claim 1, characterized by the planes being concavo-convex in shape.

55 4. In a propeller device, a plurality of superposed concavo-convex planes forming stages therebetween, conduits for individually supplying each stage with fluid, propellers in each stage, and means for rotating said propellers.

60 5. The combination set forth in claim 4, with baffles in said conduits for imparting a whirling motion to the fluids drawn through said conduits by said propellers.

65 6. The combination set forth in claim 4 characterized by the conduits and propellers being attached to each other and rotating together, and means for supporting the

parts and holding the planes against rotation.

7. In a propeller device, a plurality of concavo-convex superposed planes concentrically arranged, a support attached to said planes, concentric fluid conduits having their lower ends stepped and connected to individual planes, and propellers attached to said conduits and extending radially between said planes.

75 8. In a propeller device, a plurality of concavo-convex superposed planes concentrically arranged, a support attached to said planes, concentric fluid conduits having their lower ends stepped and connected to individual planes, and propellers attached to said conduits and extending radially between said planes, the planes having central flat parallel portions between which the propellers rotate and between which the conduits discharge.

80 In testimony whereof I affix my signature.

ERNEST W. DANIELS.
